CLAIM

The ornamental design for a material for decorative wrapping, as shown and described.

DESCRIPTION

FIG. 1 is an isometric view of a material for decorative wrapping;

FIG. 2 is a front view thereof;

FIG. 3 is a rear view thereof;

FIG. 4 is a top edge view thereof;

FIG. 5 is a bottom edge view thereof; and,

FIG. 6 is an enlarged detail view of area 6 circumscribed within FIG. 5.

In FIGS. 1-3, the broken lines on the left and right of the article depict the boundaries of the claim and form no part thereof. The broken line circle in FIGS. 5 and 6 indicate the boundaries of the detail area and form no part of the claimed design.
